(57) **CLAIM**

The ornamental design for the autonomous rider, as shown and described.

DESCRIPTION

FIG. 1 is a perspective view of an autonomous rider of the present invention;

FIG. 2 is a front view of the autonomous rider of FIG. 1; FIG. 3 is a rear view of the autonomous rider of FIG. 1; FIG. 4 is a left side view of the autonomous rider of FIG. 1; FIG. 5 is a right side view of the autonomous rider of FIG. 1;

FIG. 6 is a top view of the autonomous rider of FIG. 1; and, FIG. 7 is a bottom view of the autonomous rider of FIG. 1. The broken lines of FIGS. 1-7 form no part of the claimed design.
